US0D1093617S

(12) **United States Design Patent** (10) Patent No.: **US D1,093,617 S**
(45) Date of Patent: ** Sep. 16, 2025

(54) **FACIAL IMAGING APPARATUS**

(71) Applicant: **Canfield Scientific, Incorporated**, Parsippany, NJ (US)

(72) Inventors: **Douglas C. Canfield**, Millburn, NJ (US); **Stephen Simantiras**, Randolph, NJ (US); **Jim Larkey**, Bridgewater, NJ (US); **Daniel E. DiGregorio**, Fairfield, NJ (US)

(73) Assignee: **Canfield Scientific, Incorporated**, Parsippany, NJ (US)

(**) Term: **15 Years**

(21) Appl. No.: **29/959,314**

(22) Filed: **Aug. 24, 2024**

(51) LOC (15) Cl. **24-01**

(52) U.S. Cl.

USPC **D24/158**

Primary Examiner — T Chase Nelson
Assistant Examiner — Kelly L Gross

(57) **CLAIM**

The ornamental design for a facial imaging apparatus, as shown and described.

DESCRIPTION

FIG. 1 is a front view of a facial imaging apparatus showing the new design;

FIG. 2 is a right side view thereof;

FIG. 3 is a left side view thereof;

FIG. 4 is a top view thereof;

FIG. 5 is a rear view thereof;

FIG. 6 is an isometric view as seen from the top, front and right side thereof;

FIG. 7 is an additional front view thereof, in a rotated configuration;

FIG. 8 is an additional isometric view as seen from the top, front and right side thereof, in the rotated configuration; and, FIG. 9 is a bottom view thereof.

The broken lines in the drawings illustrate portions of the facial imaging apparatus that form no part of the claimed design.

1 Claim, 9 Drawing Sheets
